UNITED STATES PATENT OFFICE.

GEORGE G. GUY, OF BATAVIA, ILLINOIS, ASSIGNOR TO AURORA DOOR HANGER & SPECIALTY COMPANY, OF AURORA, ILLINOIS, A CORPORATION OF ILLINOIS.

FRAME FOR GRINDSTONES.

1,226,969.

Specification of Letters Patent.

Patented May 22, 1917.

Application filed September 26, 1914. Serial No. 863,613.

To all whom it may concern:

Be it known that I, GEORGE G. GUY, a citizen of the United States, and a resident of Batavia, in the county of Kane, and State 5 of Illinois, have invented certain new and useful Improvements in Frames for Grindstones, of which the following is a full, clear, and exact specification.

My invention is concerned with grind- 10 stone frames, and is designed to produce a simple frame of the class described that can be manufactured very cheaply, and that is constructed so that it can be shipped in a collapsed condition, from which it can be 15 quickly set up with a minimum of effort, and, if desired, can be readily collapsed again for further shipment.

With these objects in view, my invention consists of a grindstone frame having cer- 20 tain novel combinations and features of construction, all of which will first be fully described in this specification, and the novelty thereof particularly pointed out in the claims.

25 To illustrate my invention, I annex here- to two sheets of drawings, in which the same reference characters are used to designate identical parts in all the figures, of which,—

Figure 1 is a perspective view of the 30 frame with all the parts assembled, the stone being indicated only by dotted lines;

Fig. 2 is a view of the frame collapsed, with the stone removed, in condition for shipment;

35 Figs. 3 and 4 are views of the splashboard and seat, respectively, detached;

Fig. 5 is a section through the bearings and axle, on an enlarged scale;

Fig. 6 is a section through the seat;

40 Figs. 7 and 8 are views in section on the lines A—A and B—B, respectively, of Fig. 5;

Figs. 9 and 10 are details in section showing the connection of the lower and upper 45 ends of the side brace rods with the frame; and

Fig. 11 is a detail in section showing the connections of the treadles with the frame.

In carrying out my invention, I provide 50 two symmetrical side frames, each consisting of the horizontal top portion 20 and the legs 21 and 22, the side piece being preferably formed of a small channel bar bent into the shape shown, although I contem- 55 plate the employment of angles, or even tubes, for the side pieces. These side pieces

are braced against having their legs spread apart longitudinally of the frame by the brace rods 23 and 24, each of which is hooked through a suitable aperture 25 at 60 each end in the center of the side piece. While I might employ headed bolts and nuts, I preferably employ the rods shown, with the bent-over ends, as a cheaper construction.

The side pieces are braced from separation from each other by brace bars 26 and 27, which are conveniently secured to the adjacent legs 21 and 22 by screw-headed bolts having square nuts on the inner sides 70 of the legs coöperating with the channels to prevent said nuts turning, so that these screws can be readily driven without the necessity of holding the nuts. The lower ends are similarly connected to the legs on the 75 opposite side of the frame, and the two brace bars at each end are preferably connected at their centers by a screw 28. When the frame is to be placed in the collapsed position shown in Fig. 2, for shipment, the 80 lower screws are unfastened and the frame can be collapsed.

In addition to the end brace-bars 26 and 27, I necessarily provide other detachable 85 connections at the top of the side pieces, the first of these being the cross piece 29, which has a vertical body and the ends turned at right angles thereto, so that it can be secured to the tops 20 of the side pieces by screws and nuts in the same manner as de- 90 scribed for the brace bars 26 and 27. I utilize this cross piece 29 to support the splash- 95 board 30, which will be seen to consist of a strip of sheet metal of a suitable thickness and dimensions so that a tongue 31 stamped therefrom can be slipped over the body of the cross piece 29 to secure the splashboard removably in place. When the frame is to 100 be collapsed for shipment, one of the screws is removed, as shown in Fig. 2, and the cross piece 29 is free to be turned to permit the approach of the upper portions of the two side pieces.

Another detachable connection is formed by the seat 32, which preferably consists of a piece of sheet metal having the sides thereof slightly turned down, as indicated at 33, and having a pair of tongues 34 stamped therefrom so as to coöperate with the top sides 35 of the triangular supporting brackets 36, which are secured by screws 37 and 38 to the legs 21 at the proper elevation,

said legs being provided with a plurality of perforations 39 therein to permit of the adjustment of the seat at the desired height. When the frame is assembled, the tongues 34 engaging the tops 35 of the brackets hold the seat securely in place; and when the frame is to be disassembled and the side pieces are spread apart, the seat is released in a manner that will be readily apparent.

10 Another detachable connection between the two side pieces that forms a very important part of my invention is the axle 40 for the stone 71. The axle 40 has a central portion provided with ribs 41 to coöperate with the angles of the aperture 42 in the stone in the customary manner, and the ends of the central portion of this axle 40 are externally threaded by a coarse thread, as shown, so that the collars 43 can be screwed thereon so as to adjust and secure the stone in any desired position thereon, thus enabling me to center the stone perfectly in the frame. The ends of this central portion of the axle are provided with square recesses 44, which may 25 extend entirely through the axle, and which are designed to receive the squared ends 45 of the extensions 46 of the axle. These extensions 46 have a central cylindrical portion adapted to coöperate with anti-friction rollers 47 placed between said cylindrical portion 46 and bearing brackets 48 bolted or otherwise secured on the tops 20 of the side pieces, and having cylindrical interiors adapted to receive the rollers 47 and form a 30 roller bearing. The extensions of the axles are provided with flanges or collars 49 adapted to engage the ends of the central portion and to hold the inner ends of the anti-friction rollers 47 in place. These extensions are also provided with squared, reduced outer ends 50, upon which are secured the hubs 51 of the crank arms 52. The extensions 46 are formed of some material such as malleable castings, so that when the 35 cranks are fitted in place they can be swaged on and the cranks secured in place. The extensions also have apertures therethrough, and when the parts are assembled, the bolt 53 is passed through the extensions and the 40 axle, and the nut 54 screwed thereon, so that all the parts are held in place. When it is desired to knock down the frame for shipment, all that is necessary is to remove the bolt 53, when the extensions can be drawn 45 out from the center of the axle as the side pieces are separated, and the frame is ready to ship, with the bearings in place and prevented from any possible displacement. This is a very marked advantage in the mer- 50 chandising of these frames, as any ordinary construction that permits of the loss or misplacement of the roller bearings is highly objectionable, as such loss is liable to occur during shipment, or the misplacement to occur 55 when the frame is being set up by the

purchaser. The ends of the cranks may be provided with any suitable connections 55 having an aperture 56 therein, through which aperture is passed the doubly curved end 57 of the connecting rods 58, which have 60 their lower ends formed with hooks 59 adapted to catch in the loops 60 formed in the treadles 61, which treadles are preferably composed of flat bars bent into the shape shown, with the small loops 60, the 65 large loops 61^a forming the footholds of the treadles. The ends are separated a sufficient amount to embrace the lower ends of the legs 21, which have loops 62 struck up therefrom, so that pins 63 passed through suitable apertures in the treadles and through the loops 62 can be secured in place by the use of cotter pins 64, making a very cheap and durable fulcrum attachment for the 70 treadle levers.

80 While I have herein shown and described a novel axle and crank construction, I do not herein claim the same, but reserve it for a divisional application.

85 While I have shown and described my invention as embodied in the form which I at present consider best adapted to carry out its purposes, it will be understood that it is capable of modification, and that I do not desire to be limited in the interpretation of the 90 following claims except as may be necessitated by the state of the prior art.

95 What I claim as new, and desire to secure by Letters Patent of the United States, is:

1. In a collapsible grindstone-frame, the 100 combination with a pair of side pieces each comprising a horizontal top and two legs, of a pair of crossed brace pieces at each end forming the only connections between the legs of the side pieces pivoted to each other and each detachably secured at one end to one of the side pieces and forming the only connections between the legs of the two side pieces, and detachable connections between the tops of said side pieces, which when detached, permit the side pieces being collapsed toward each other without changing their shape.

105 2. In a collapsible grindstone-frame, the combination with a pair of side pieces each comprising a horizontal top and two legs, of a pair of detachable brace pieces at each end, and detachable connections between the tops of the side pieces, which when detached, permit the side pieces being collapsed toward each other without changing their shape, said detachable connections including a detachable seat.

110 3. In a collapsible grindstone-frame, the combination with a pair of side pieces, of a pair of detachable brace pieces at each end, and detachable connections between the tops of the side pieces, said detachable connections including a detachable seat, consisting of a piece of sheet metal having tongues 115

struck downward therefrom, and brackets permanently secured to the side pieces with which the tongues coöperate.

4. In a collapsible grindstone-frame, the combination with a pair of side pieces each comprising a horizontal top and two legs, of a pair of detachable brace pieces at each end forming the only connections between the legs of the side pieces, and detachable connections between the tops of the side pieces which when detached, permit the side pieces

being collapsed toward each other without changing their shape, said detachable connections including an axle for the stone, extensions of said axle, bearings in the side pieces through which the extensions pass and in which they are permanently held, and a bolt for securing said extensions to the axle.

5. In a collapsible grindstone-frame, the combination with a pair of side pieces, of a pair of detachable brace pieces at each end, and detachable connections between the tops of the side pieces, said detachable connections including a brace detachably connected at one end to the top of one side, and a splashboard having a tongue struck up therefrom coöperating with the brace to detachably secure the board thereto.

6. In a collapsible grindstone-frame, the combination with a pair of side pieces each comprising a horizontal top and two legs, of a pair of detachable brace pieces at each end, and detachable connections between the tops of the side pieces, which when detached, permit the side pieces being collapsed toward each other without changing their shape, said detachable connections including a detachable seat, a brace detachably connected at one end to the top of one side, a splashboard detachably connected to said brace, an axle for the stone, extensions of said axle, bearings in the side pieces through which the extensions pass and in which they are permanently held, and means for removably securing said extensions to the axle.

7. In a grindstone frame, the combination with a pair of inverted U-shaped side-pieces, each made of an integral bar of metal, of connections for holding the same spaced apart, and sufficiently detachable therefrom to permit the side pieces being collapsed toward each other.

8. In a grindstone frame, the combination

with a pair of inverted U-shaped side-pieces each made of an integral bar of metal, of a pair of crossed brace-pieces at each end pivoted to each other and each adjustably secured at one end to one of the side pieces and forming the only connections between the legs of the two side pieces, and connections between the tops of said side pieces, and sufficiently detachable therefrom to permit the side pieces being collapsed toward each other.

9. In a grindstone frame, the combination with a pair of inverted U-shaped side-pieces each made of an integral bar of metal, of a pair of detachable brace-pieces at each end, and detachable connections between the tops of the side pieces, said detachable connections including a detachable seat, said brace-pieces, connections, and seat being detachable to permit the side pieces being collapsed toward each other.

10. In a grindstone frame, the combination with a pair of inverted U-shaped side-pieces each made of an integral bar of metal, of a pair of detachable brace-pieces at each end, and detachable connections between the tops of the side pieces which when detached permit the side pieces being collapsed toward each other, said detachable connections including an axle for the stone, extensions of said axle, bearings in the side pieces through which the extensions pass and in which they are permanently held, and a bolt for securing said extensions to the axle.

11. In a collapsible grindstone-frame, the combination with a pair of side pieces, of brace rods 23 and 24 extending through apertures in the side pieces and having turned-up ends engaging therewith, a pair of crossed brace pieces at each end pivoted to each other and each detachably secured at one end to one of the side pieces, and detachable connections between the tops of said side pieces.

In witness whereof, I have hereunto set my hand and affixed my seal, this 23rd day of September, A. D. 1914.

GEORGE G. GUY. [L.S.]
